GEORGE S. BINCKLEY, OF LOS ANGELES, CALIFORNIA.

DISCHARGE-VALVE.

1,243,134.

Specification of Letters Patent. Patented Oct. 16, 1917.

Application filed November 18, 1914. Serial No. 872,763.

To all whom it may concern:

Be it known that I, GEORGE SYDNEY BINCKLEY, a citizen of the United States, residing at Los Angeles, in the county of Los Angeles and State of California, have invented new and useful Improvements in Discharge-Valves, of which the following is a specification.

This invention relates to high pressure water gates or discharge valves for controlling the discharge of large volumes of water at high heads. Such a condition exists at dams and outflow points of water systems of various kinds. A serious problem with which hydraulic engineers have been confronted has been found in the tremendous velocity with which these large volumes of water flow from a reservoir or other impounding structure or basin, under high head, into either closed or open conduits for conducting the water to points of consumption or use or further storage. The unobstructed or unmodified discharge of such great volumes of water at high head, through gates of the kind heretofore used, often produces tremendous effects by setting up a vibration that may constitute a danger to the masonry of dams and the organization of conduits, basins, ditches or other structures or impounding or conveying means, and also produces the disturbing roar or noise which ordinarily accompanies such discharges. When such violent discharges of water are permitted damage to the gate structures and other discharging or conveying means is an inevitable result, due to the erosive action of silt, sand or other abrasives in the water. Thus, the problem has been to so control the velocity of the water as to limit the effect of the contained abrasives, and eliminate the dangerous vibration, and the roar or noise accompanying a discharge at high velocity.

A further problem to be dealt with in this connection is that of operation or control of the gate itself, which is opposed to the pressures which in the aggregate are often tremendous. Discharge gates of this class are likewise subject to derangement due to the tremendous pressure and tremendous velocities affecting the same.

It is the object of the present invention to provide a discharge gate or valve which will eliminate all of the objectionable features above mentioned, which may be operated or

controlled with extreme simplicity and but little manual effort, which when once installed will operate for practically an unlimited period of service without necessitating repair or replacement of parts, and which will generally provide for the discharge of large volumes of water under widely varying heads at a predetermined maximum velocity, and in a noiseless, or substantially noiseless, vibrationless and non-wearing manner.

Further objects of the invention consist in the provision of a discharge gate or valve of the general character stated which will be relatively simple and inexpensive in construction and organization when its features of superiority are taken into account, which will be unfailing and positive in operation, and which will be generally superior in efficiency and serviceability.

In carrying the invention into effect, I provide means whereby the discharge or outflow of water may be primarily determined, such means constituting in effect a valve proper with which means are associated controlling means determining the working position of such valve means, and also are associated means for modifying the velocity of the outflowing water by converting a certain proportion of its kinetic energy into heat. These latter means are related in their effect to the several positions which the valve means can assume, so that the conversion of such kinetic energy into heat is related to the head of water supplying such kinetic energy.

With the above and other objects in view, and the above generally stated means entering into the embodiment of the same, the invention consists in the novel and useful provision, formation, combination, association and inter-relation of parts, members and features, all as hereinafter described, shown in the drawing and finally pointed out in claims.

In the drawing:

Figure 1 is a central vertical sectional view of a discharge valve or water gate organized to embody the invention, the same being indicated as installed in working position at the base of a dam confining a body of water;

Fig. 2 is a detail transverse sectional view of the same, taken on the line x^2-x^2 , Fig. 1; and,

Fig. 3 is an enlarged fragmentary detail view of a portion of the showing in Fig. 1, the valve being shown partially opened.

Corresponding parts in all the figures are 5 designated by the same reference characters.

Referring with particularity to the drawing, the improved water gate or discharge valve is shown as comprising valve means A and controlling or operating means B for 10 the valve means, such discharge valve having an intake orifice *a* and a discharge orifice *b* which may lead to the open or to a discharge conduit, pipe or the like *c* whereby the water may be conducted to a point of 15 storage or use. C designates means associated with the valve means A for converting the kinetic energy of the moving water, taken from behind the dam D or some other source, in part into heat, so as to reduce the 20 velocity of the water received at the orifice *a* and discharged at the orifice *b*, whereby the water issues at the discharge orifice *b* at a predetermined velocity, which will be such that damaging vibration or impact and noise 25 of discharge will be eliminated. The reduction in velocity through the performance of the function of the means C likewise prevents derangement of the working parts of the discharge valve, both by attack of the 30 water itself and of such cutting or abrading content as the water may have. The velocity of the water being reduced, the operation or control of the valve means A itself is rendered easier, requiring less voluntary 35 controlling or operating effort. The control means B utilizes water at the same head as that taken in at the orifice *a*, the amount of such water at such head admitted to the valve means for the purpose of controlling 40 the same being regulated by valve means *d*. The water so utilized in the operation or control of the valve means *a* is discharged into the outflowing stream of water issuing at the orifice *b*, and such discharge is regulated as to its volume by valve means *e*. 45 Leakage from the means C to the valve means *a* is likewise disposed of under control of the valve means *e* and co-operates with the water introduced under control of 50 the valve means *d* in maintaining the valve means *a* in proper working position, so that such valve means *a* will maintain itself at all times to provide the same outflow velocity at the orifice *b* as required by changes 55 in head of water admitted at the orifice *a*, in accordance with the disposition of the valve means *d* and *e* under voluntary control. Thus, with these valve means *d* and *e* set voluntarily to provide for changes in 60 head, the leakage factor mentioned will co-operate with the valve controlling water admitted by the valve means *d*, to prevent material fluctuation of the valve means *a* from the position related to the head primarily 65 determined by the valve means *d* and, the

valve means *e*. The means C are so organized that their effectiveness at any position of the valve means A is related to the head obtaining at that time so that a greater or less effect always exists with respect to 70 a corresponding greater or lesser head, to the end that a constant velocity of outflow of water at the orifice *b* is maintained.

Irrespective of the inter-relation of the action of the leakage water and the controlling water affecting the valve means A, the said valve means A are so organized that the material fluctuation of the valve means A, with the valve means *d* and *e* set as predetermined, is prevented. 75

In the particular construction and inter-relation of parts, members and features shown in the drawing, the discharge valve or water gate shown therein, including the means C, comprises a shell or casing 6 which 80 is flanged as at 7, to rest upon the floor of the reservoir or at the base of the dam structure D, such casing preferably being as shown materially surrounded by or embedded in the masonry of the dam. The casing 6-90 includes an enlarged top portion 6^a and relatively contracted bottom portion 6^b, the top portion having a detachable top plate or cover 6^c permitting installation of the contained features, and the contracted bottom portion 6^b terminating in a discharge head 6^d provided with the discharge orifice *b* which may lead to the discharge pipe or conduit *c*. Within the top plate or cover 6^c is provided the inlet orifice *a*, centrally 95 thereof, and covered by a suitable screen device 8. Stationed within the contracted bottom portion 6^b of the casing 6 is a cylinder 9, the casing 6 being preferably likewise cylindrical, and such cylinder 9 being 100 concentric with the contracted portion 6^b of the casing 6. The valve means A, including a hollow cylindrical piston valve 10, is mounted to play within the cylinder 9 and having an annular outwardly projecting 105 rim 10^a which has a working fit within such cylinder 9, its upward movement being limited by an annular intruding seat 11 bolted to the cylinder 9 as at 12; the upward movement of the entire piston valve 10 being 110 simultaneously interrupted by a valve seat 12^a at the orifice *a*. The piston valve 10 is provided with a cylindrical stem 13 which is guided, in the vertical play of the valve 115 10, in a cylindrical guide 14 fixed to or integral with the bottom of the cylinder 9, and ranging slightly above the zone of the rim 10^a when the same is in highest position. This stem 13 is provided with a helical external groove or channel 13^a extending 120 throughout its entire length, and whereby the interior of the hollow piston valve 10 may communicate variably with the interior of the valve stem guide 14 from the lower end of which leads a discharge 125 130

pipe 15 which is controlled by the valve means *e*. Communicating with the lower portion of the cylinder 9 is a pipe 16 whereby water is admitted to the cylinder 9 under control of the valve means *d*, such water being taken from the body thereof, the discharge of which is controlled by the valve means *A*. The valve means *d* may comprise a puppet valve or other valve device 17 adapted to close or open the pipe 16 coöperating with a suitable seat 18 at the upper end of said pipe, such valve device having a stem 19 whereby the position of the valve device may be manually or otherwise controlled. The valve means *e* may comprise any suitable valve device 20, such as a plug valve or stopcock, having a stem 21 ranging in juxtaposition with the stem 19 so that both valve devices 17 and 20 may be conveniently controlled from the same point or by the same operator or simultaneously.

The means *C* for converting a portion of the kinetic energy of the water admitted at the orifice *a* into heat, comprises a plurality of concentric H-shaped annuli 22, separated by annular spaces 23 which at points are bridged by spaced webs 24 to hold the annuli of each such grid in assemblage; other spaced webs 25 being provided beneath and above the horizontal members of the H-shaped annuli to space each grid from the next adjacent grid, so that free circulation of water may take place through the annular spaces of all the grids, from the uppermost to the lowermost of the same, and thence downwardly to the discharge head 6^a and the orifice *b* thereof. The innermost and outermost annuli 22 of certain of the grids are mutilated to provide for the proper vertical staggered relation of the annular spaces 23, in the grids which are all to be accommodated within the top portion 6^a of the casing 6 and to substantially fill such top portion, with the exception of the space within which the piston valve 10 is vertically movable. The top of the chamber within the top portion 6^a of the casing 6 is devoid of the grids *f*, as at 26, such chamber portion 26 being highest at the central portion thereof and diminishing in height outwardly to provide proportionate distribution of the water to the annular spaces 23 in the uppermost grid *f*; and such annular spaces 23 may be of varying widths or capacities as required to further establish a substantially even distribution of the water throughout the whole system of grids.

I do not lay any claim to the specific operating means for the valve means *A*, and these operating means *B* for the valve means *A* may manifestly be widely varied in construction in accordance with the service to be dealt with.

The operation, method of use and advantages of the improved water gate or dis-

charge valve constituting the invention will be readily understood from the foregoing description, taken in connection with the accompanying drawing and the following statement:—

In operation of the controlling means *B*, including the valve means *d* and *e*, the latter are manually or otherwise set or changed in set to correspond to the head of the water received at the orifice *a*, and changes in such head, or to station the valve 10. Normally the valve device *d* will be unseated to permit the column of water admitted thereby to the cylinder 9 to hold the piston valve 10 seated, the valve device 20 being closed. If now it is desired to pass water through the water gate or discharge valve embodying the invention, the valve device *d* will be brought into position with respect to its seat so that only the proper amount of water will be passed through the cylinder 9 and circulated within the hollow piston valve 10 and discharged through the pipe 15, the valve device 20 being suitably opened for the purpose, to cause the piston valve 10 to leave its seat 12 sufficiently to establish proper communication between the chamber containing the means *C* in proportion to the head of water supplied at the orifice *a*. The lower the head, the closer is the valve device *d* brought to its seat and the wider is the valve device 20 opened. The total area of the upper working end of the piston valve 10 is less than the total area of the inner surface thereof plus the lower working surface of the rim 10^a, so that the piston valve 10 may be held to its seat, as stated, when the valve means *d* is opened and the valve means *e* is closed. Now with the valve device *e* partly opened, and the valve device *d* partly opened in proportion to the head of the water at the orifice *a*, water passes from the pipe 16 into the cylinder 9 and upwardly into the hollow piston valve 10, but is permitted to escape from the latter and into the hollow guide 14 through the helical chamber 13^a upon the stem 13, and thence outwardly through the pipe 15 and past the valve device 20. This permits the piston valve 10 to descend slightly; but as it does so more and more of the passage 13^a is cut off from direct communication with the interior of the hollow piston valve 10 by its entry into the hollow guide 14, diminishing discharge of water through such channel 13^a, which causes the piston valve to come to rest in the normal position determined by the intake of water through the pipe 16 and the discharge of water through the pipe 15. Water leaking into the cylinder 9 from the now open chamber inclosing the means *C*, past the rim 10^a, will add to the pressure within the cylinder 9 and the piston valve 10, but this will be compensated by diminishing the intake at 130

the valve device 17 so that the valve 10 will in reality be in a position of equilibrium determined by the positions of the valve devices 17 and 20, the leakage, and the resistance to flow through the guide-incased channel 13^a on the one hand, and the pressure of the water on the head of the valve 10 on the other hand. Thus, the piston valve 10 is maintained at the proper height 5
10 in accordance with the opening of the valve devices 17 and 20 and further in accordance with the head of water supplied at the orifice *a*. After such head of water falls the piston valve is permitted to assume a 15 lower position corresponding to the diminished rate of discharge of water in the orifice *b* and the velocity of the water at such discharge orifice *b*, diminished by the action of the means *C*, the water circulating 20 through the grids *f*, in tortuous flow, it being baffled by such progress, setting up frictional retardation in which a portion of the kinetic energy of the water is converted into heat, so that the water issuing from the 25 orifice *b* will be at a lower velocity than would be possible without the interference of the means *C*.

It results from the utilization of the improved water gate or discharge valve described that, by reason of the diminution of the velocity of the water issuing therefrom, the resultant vibration, to a degree harmful to dams and the like, is eliminated together with the attendant noise. Likewise, the cutting action of any abrading content of the water is reduced because of the diminution of velocity of the water; and this diminution of velocity likewise eliminates dangerous pounding and other attack upon the working parts of the water gate, tending to derange or impair the working efficiency of the same. 30
35
40
45
50
55

It will be seen that as the piston valve 10 descends or assumes lower stations of elevation, an increasingly smaller grid or baffle zone is required to be traversed by the water flowing through the casing 6. Thus, at higher heads, a greater baffle action takes place, in proportion to the greater requirement for converting kinetic energy into heat to prevent attainment of a high velocity of the water. The baffling action, at any head of water, is thus properly proportioned to such head, by the station of the piston valve 10, to provide the proper energy conversion for such head. 55

The entire device or apparatus is relatively compact in form and may be conveniently and effectually controlled, the manipulation of the valve means *d* and *e* being performed manually or in any suitable manner; and on observation of changes in head of the water behind the dam or the like the said valve means may be regulated to keep 60
65 the working position of the piston valve 10

consistent with such changes in head. The apparatus effectively transforms the action of water discharged in large volumes at high heads from a dangerous, destructive, and annoying action into a smooth, harmless 70 and safe operation, in the several respects of which mention has been made, and such others as will readily occur to those skilled in the art.

It is manifest that many variations may 75 be made with respect to the provision, construction and inter-relation of parts, members and features, in practising the invention, without departing from the spirit of the invention and a fair interpretation 80 thereof.

Having thus disclosed my invention, I claim and desire to secure by Letters Patent:

1. Improved apparatus of the character disclosed, comprising a chamber provided 85 with an inlet orifice and an outlet orifice, valve means controlling traverse of said chamber by fluid, means within the chamber for converting a portion of the kinetic energy of the fluid traversing the chamber 90 into heat, and means for controlling said valve means in accordance with variations in rate of fluid flow; said valve means in the operation thereof providing for variable action of said second named means in accordance 95 with variations in rate of fluid flow.

2. Improved apparatus of the character disclosed, comprising a chamber provided with an inlet orifice and an outlet orifice, 100 valve means controlling traverse of said chamber by fluid, means within the chamber for converting a portion of the kinetic energy of the fluid traversing the chamber into heat, and means for controlling said 105 valve means in accordance with variations in rate of flow; said valve means in the operation thereof providing for variable action of said second named means in accordance with variations in rate of fluid flow; 110 said second named means comprising a baffle device.

3. Improved apparatus of the character disclosed, comprising a chamber provided with an inlet orifice and an outlet orifice, 115 valve means controlling traverse of said chamber by fluid, means within the chamber for converting a portion of the kinetic energy of the fluid traversing the chamber into heat, and means for controlling said 120 valve means in accordance with variations in rate of flow; said valve means progressively limiting the zone of effective action of said energy converting means in the actuation of said valve means. 125

4. Improved apparatus of the character disclosed, comprising a chamber provided with an inlet orifice and an outlet orifice, valve means controlling traverse of said chamber by fluid, means within the chamber 130

for converting a portion of the kinetic energy of the fluid traversing the chamber into heat, and means for controlling said valve means; said converting means comprising surfaces materially extended laterally of the path of flow.

In testimony whereof, I have signed my

name to this specification in the presence of two subscribing witnesses.

GEORGE S. BINCKLEY.
